US00D523063S

(12) **United States Design Patent** (10) **Patent No.:** **US D523,063 S**
Tu (45) **Date of Patent:** **** Jun. 13, 2006**

(54) **PRINT CARTRIDGE**

(75) Inventor: **Chun-Chang Tu**, Taipei (TW)

(73) Assignee: **Hi-Touch Imaging Technologies Co., Ltd.**, Taipei Hsien (TW)

(**) Term: **14 Years**

(21) Appl. No.: **29/211,150**

(22) Filed: **Aug. 12, 2004**

(30) **Foreign Application Priority Data**

May 28, 2004 (TW) 93303160

(51) **LOC (8) Cl.** **18-01**

(52) **U.S. Cl.** **D18/12**

(58) **Field of Classification Search** D18/12,

D18/36, 40, 43, 44, 56; D16/237, 246-250;
D14/474-484; 399/24-28, 110-112, 116,
399/119, 121, 122, 222-224; 347/49, 86,
347/87, 214; 400/194, 196, 207, 208

See application file for complete search history.
